UNITED STATES PATENT OFFICE.

BERNARD P. SCHILTZ, OF CLEVELAND, OHIO, ASSIGNOR TO THE P. A. GEIER COMPANY, OF CLEVELAND, OHIO, A CORPORATION OF OHIO.

ARBOR PRESS.

Application filed October 21, 1920. Serial No. 418,458.

To all whom it may concern:

Be it known that I, BERNARD P. SCHILTZ, a citizen of the United States of America, residing at Cleveland, in the county of Cuyahoga and State of Ohio, have invented certain new and useful Improvements in Arbor Presses, of which the following is a specification.

My invention relates to improvements in arbor presses and has for its object the provision of mechanism enabling the user readily to vary the power exerted by the press, as by locking it so as to be directly actuated by the lever or by interposing variable gears.

Moreover, the improved structure, which I shall describe with some detail, is extremely compact, being contained in a relatively small gear casing adapted for actuation by the operating lever and closely adjacent to the plunger of the arbor press.

Within said gear casing there are provided a stationary gear, its meshing gear, a shifting gear adapted to interlock with the latter or with the casing, and a ratchet-actuating gear meshing with said shifting gear. These members, reacting upon the usual pinion shaft, serve to actuate the plunger and rack of the arbor press in accordance with the locking arrangement of the shifting gear and the ratio of the adjusted gearing.

The features of my improvement and the mode of operation may best be described in connection with the accompanying drawings, wherein:

Fig. 1 is a fragmentary view in front elevation, partially sectioned illustrating the gear casing and lever.

Fig. 2 is a side view thereof with the cover plate removed, together with the outer meshing gears.

Fig. 3 is an irregular section on line A—G, Fig. 2.

Fig. 4 is a side view similar to Fig. 2 with the outer gears in position.

Fig. 5 is a fragmentary perspective view of the ratchet mechanism pawls and springs.

Fig. 6 is a fragmentary view partly in section to show the frame and gear casing

and partly in elevation to show the relation of the gears; the section being indicated by line H—N, Fig. 4.

Fig. 7 is a side view of the arbor press to which my improvements have been applied, and

Fig. 8 is a fragmentary perspective view of the upper portion of the press with the gear casing and lever removed.

Throughout the several figures of the drawings I have employed the same character of reference to indicate similar parts.

Referring first to Fig. 7, the general features of the arbor press are therein shown in connection with a compact gear casing near the upper left hand portion of said figure wherein are contained my improved actuating means. I may advantageously itemize the several principal members of such arbor press and actuating means as follows: The gear casing is indicated by 1 and its removable cover by 2; the pinion shaft by 3; the operating lever by 4 and its set screw by 14; the gear shift stud by 5; the cover screws by 6; the shifting gear by 7 and its set screw by 8; the reduction gear by 9; the adjusting screw, spring and detent-ball, respectively, by 10, 11 and 12; the stationary gear by 13; the pawl springs by 15, 16; the pawl-actuating gear by 17; the contained pawls by 18, 18'; the tapered locking pin by 19 and its associated hand wheel by 20; the bored standard by 21 and its contained rack and plunger by 22; the actuating pinion by 23 and the press body by 24.

Since there are present no variations from or improvements upon a well known press body 24, the outline view thereof will be sufficient for illustrating the use of my improvements without further description and I will direct my further explanation of the invention to the novel actuating means. A slotted, tubular stud 21', integral with the standard 21, rotatably mounts the gear casing 1, but locks the stationary gear 13 against rotation. Meshing with said gear 13 is the reduction gear 9. Inasmuch as these gears require merely partial peripheral engagement, they are but partially cut, preferably, as shown.

As best shown in Fig. 6, the shifting gear 7, which is secured upon the longitudinally movable stud by the set screw 8, may be ac-

tuated into engagement with the reduction gear 9, as there illustrated, so that it will be rotated by the latter through a small arc, or said gear 7 may be locked alternatively by engagement with the rib 2' provided on the interior of the cover, as best shown in Fig. 3. It will be observed that the inner end of said stud 5 is provided with two annular grooves, either one of which 10 may be engaged by the ball 12 to hold the stud and gear in one or the other of their operative positions.

Meshing, in turn, with the gear 7 is the annular pawl-actuating gear 17 carrying 15 within its recesses the pawls 18, 18'. Alternatively one or the other of these pawls will engage with the ratchet teeth of the ratchet wheel 3' provided at the outer end of the pinion shaft, by which said shaft is 20 adapted to be rotated step by step. Referring to Fig. 5, it is seen that the pawls 18, 18', are respectively engaged terminally by the annular springs 15, 16, so that the tendency is constantly to engage the pawls 25 with the ratchet teeth. The pawls are each provided with an extended end 13'', which engage the cams 13' alternatively and serve to lift one or the other or both out of such engagement, in order to free the ratchet 30 wheel and its pinion shaft.

It will be understood, of course, that the ratios of the gears may be varied merely by substituting meshing gears of different sizes, but with the members constructed and 35 proportioned as shown in the drawings, and adjusted as illustrated in Fig. 6 with the gears 7 and 9 interlocked through their tongue and groove construction, the operative ratio is approximately three to one. 40 Thus a very material increase in leverage is provided as applied through the gearing and pinion shaft to plunger 22.

In order to afford more rapid actuation 45 of the plunger, however, it is necessary only to withdraw the gear shift stud 5 and its connected gear to their outermost positions, with the groove indicated by the dotted line, Fig. 3, in engagement with the rib 2', whereupon said gear 7 will be locked to 50 rotate with the gear casing and act as a direct drive for the pawl-actuating gear 17, with which it invariably is in mesh, and about which it is otherwise concentrically 55 rotated, when locked in operative engagement alternatively with the gear 9.

This latter operation, when the maximum power is desired, may bear a little further explanation. Thus, referring to Fig. 2, it 60 will be recalled that the gear 13 is held stationary while the gear casing and its associated gear 9 are concentrically rotated about the same. This, obviously, imparts a partial counterclockwise rotation to the gear 9 within the casing, whenever the actuating lever 4 is depressed. A slow, identical coun-

terclockwise rotation must also be imparted to the shifting gear 7 when locked in operative relation with this reduction gear 9, and, as a result, the pawl-actuating gear 17 is given a partial but still slower counterclockwise rotation, whereby the pawl 18 in engagement with the ratchet wheel 3' will serve similarly to rotate the pinion shaft and depress the plunger of the arbor press. 70

Accordingly, it will be appreciated that 75 a ready and highly efficient provision is made for instantly converting the power moment of the press from one ratio to another, depending upon the work in hand and accomplished merely by the shifting of the variable gear stud. 80

While I have explained my improvements as embodied in an arbor press, the actuating mechanism of my invention is capable of much wider application, as for example 85 with lifting jacks, or screw-actuated mechanism, and I do not intend to restrict it to the limited use and details herein specified. Thus, in the appended claims I wish to be understood, in defining the gear or gearing 90 for varying the ratio of power and speed, as intending mechanical equivalents thereof, rather than the particular types of interrelated and mutilated gear-wheels herein shown. 95

Having now described the preferred embodiment of my invention, I desire to claim, together with such departures therefrom or modifications as may be made by the exercise of expected skill in the art, the following:

1. In actuating mechanism of the class described, the combination with a driving pinion associated with a plunger, of an actuating gear therefor, a stationary gear, 105 a reduction gear meshing with the latter, connecting means for driving the actuating gear from the reduction gear and means whereby the power to the mechanism may be applied directly without reduction, substantially as set forth.

2. In actuating mechanism of the class described, the combination with a driving pinion associated with a press plunger, of an actuating gear operatively connected for 115 rotating the pinion, a stationary gear, a reduction gear meshing with the latter, and a shifting gear adapted to be operatively associated with the reduction gear and meshing with said actuating gear; all in association with means for applying power to the mechanism as a whole, substantially as set forth.

3. In actuating mechanism of the class described, the combination with a pivoted 125 gear casing and its operating lever, of a stationary gear within the casing, a meshing reduction gear, an actuating gear, and an interposed shifting gear normally meshing with the latter and provided with means 130

for alternatively locking it with respect to the casing or for rotation by the reduction gear, substantially as set forth.

4. In combination with an arbor press and its plunger, a driving pinion for said plunger, an actuating gear operatively connected therewith, a concentrically pivoted gear casing and its operating lever, a stationary gear therein, a reduction gear, and a shifting gear in mesh with the actuating gear and adapted alternatively to be locked with respect to the casing or for actuation by and with the reduction gear, substantially as set forth.
5. The combination with a pivoted gear casing and its operating lever, of a pinion shaft, a stationary gear and an actuating gear for the pinion shaft all concentrically mounted within the casing, an eccentrically

mounted reduction gear meshing with the stationary gear, and a shifting gear adapted alternatively to be locked for rotation with the latter or with respect to the gear casing, and meshing with the actuating gear, substantially as set forth.

6. In actuating mechanism of the class described, the combination with a driving pinion associated with a plunger, of an actuating gear therefor, a stationary gear, a reduction gear meshing with the latter, shiftable connecting means for driving the actuating gear from the reduction gear, and means whereby the power of the mechanism may be applied directly without reduction, substantially as set forth.

In testimony whereof I do now affix my signature.

BERNARD P. SCHILTZ.
